UNITED STATES PATENT OFFICE.

WILLIAM EDWARD WALSH, OF NEW HAVEN, CONNECTICUT.

AUTOMATIC TRAIN-STOP.

1,329,258.

Specification of Letters Patent. Patented Jan. 27, 1920.

Application filed December 26, 1918. Serial No. 269,333.

To all whom it may concern:

Be it known that I, WILLIAM EDWARD WALSH, a citizen of the United States, residing at New Haven, in the county of New Haven and State of Connecticut, have invented a new and useful Improvement in Automatic Train-Stops; and I do hereby declare the following, when taken in connection with the accompanying drawings 10 and the characters of reference marked thereon, to be a full, clear, and exact description of the same, and which said drawings constitute part of this application, and represent, in—

15 Figure 1 a perspective view of my improved train-stop mechanism showing the operating lever in the raised position.

Fig. 2 a broken perspective view showing the emergency air-tank and conduit to air 20 governor as arranged below the floor of the engine cab.

Fig. 3 a perspective view of the operating mechanism with the lever in the closed position or position after passing a danger 25 signal.

Fig. 4 a top or plan view of the locking hook for holding the lever in its lowered position.

Fig. 5 a sectional view on the line *a—a* 30 of Fig. 4.

Fig. 6 a perspective view of the operating cam at signal points.

Fig. 7 a similar view with the operating cam in the raised position.

35 This invention relates to an improvement in automatic train stops, and particularly to automatic stops which are adapted to be operated at signal points by means of mechanism operated from a signal tower, and 40 which, when the track is clear, may be passed without hindrance, and which if the signal is set will operate the air brake mechanism to bring a train to a stop.

The object of the invention is to provide 45 simple and effective means for operating the brake mechanism in case the engineer fails to obey the danger signal set against him; and the invention consists in the construction hereinafter described and particularly recited in the claims.

In carrying out my invention I employ a one-way valve 1 which is connected to a plate 2 secured by bolts 3 to a metal flash block 4 fastened to the roof of an engine 55 cab, the size of this block being determined

by the height to which the device is to extend above the cab roof. Connected with the plate 2 are two steel posts 5—5 in the upper ends of which are rearwardly extending stops 6—6. Connected with the 60 valve shaft 10 projecting at opposite sides of the valve 1 are lever arms 7 the outer ends of which are connected by a pin 11 upon which the wheel 12 is mounted for the purpose as will hereinafter appear. Connected with the lever 7 and with the posts 5 are springs 8 the tendency of which is to draw the levers against the ends of the stops 6. The valve 1 is connected by means of a pipe at one end with the main train line 70 and with a pipe from the other end to the emergency air tank 13 which is provided with an automatic reducing valve 14, this emergency tank being secured to the underside of the floor of the engine cab by means 75 of straps 15. In the normal position the lever arm 7 stands upright so as to present a roller 12 in the line with a cam plate 21 connected by angle irons 22 with a beveled frame 23 which in turn is connected by 80 hinges 25 with a fixed beam 24 arranged at a signal point. This cam plate 21 may be swung into or out of the path of the roller 12 by means of wires 26, from a signal tower, running over pulleys 27 mounted in a transverse plate 28 riveted to the beam 24. When the signal is clear the cam 21 is thrown upward as indicated in Fig. 7 of the drawings so that the roller 12 will pass without obstruction. In case of danger the cam plate 90 will be swung down, as shown in Fig. 6 of the drawings, so as to stand in the path of the roller 12 which will contact with the cam plate and be thrust down into the position shown in Fig. 3, and this movement of 95 the levers opens the valve 1 and automatically applies the brakes. As the lever arms 7 are depressed they are engaged by a hook 16 pivotally mounted in a plate 17 which rests upon a block 18 in order to properly 100 place it. This hook 16 rests against a stop 19 and is provided with a handle in position to be operated by the engineer, the movement of the hook in opening being against the tension of a spring 20 which 105 normally acts to hold the hook against the stop 19. In case the engineer fails to observe a signal set against him the valve will be operated to set the brakes and the valve-operating mechanism will be locked until 110

released by the engineer operating the hook 16 to free the lever arm 7 which will again rise.

I claim:—

- 5 1. The combination with a valve with connection to the main train line and an emergency air tank, of lever arms connected with the valve for operating the same, a roller connected with the outer ends of said lever arms, stops to limit the upward movement of said lever arms, springs normally tending to draw the lever arms against said stops, means for holding the lever arms in the depressed position, and a cam-plate 10 adapted to be turned into the path of the said roller.
- 15 2. An automatic train stop comprising a valve, connections between the valve and the main train line and to an emergency air tank, lever arms connected with said valve, 20

a roller mounted in the ends of said lever arms, springs normally tending to hold the lever arms in a vertical position, a hook adapted to engage with one of said lever arms when in the depressed position, and an inclined cam plate adapted to be swung into or out of the path of said roller. 25

3. An automatic train stop comprising a valve, a plate on which the valve is mounted, posts connected with said plate, stops connected with the upper ends of said posts, lever arms operating said valve and arranged in the path of said stops, a roller mounted between the outer ends of said lever arms, means for locking the levers in the depressed position, and an inclined cam plate arranged to be swung into or out of the path of said roller. 30 35

WILLIAM EDWARD WALSH.
